EYE GLASS CASE

Emanuel Nathan, South Orange, N. J.

Application June 22, 1953, Serial No. 25,599

Term of patent 14 years

(Cl. D57—1)

To all whom it may concern:

Be it known that Emanuel Nathan, a citizen of the United States, residing at 303 Montague Place, South Orange, in the county of Essex and State of New Jersey, has invented a new, original, and ornamental Design for an Eye Glass Case, of which the following is a specification, reference being had to the accompanying drawing, forming part thereof.

In the drawing:

Figure 1 is a front elevational view of an eye glass case, showing my new design, the opposite side of the case being plain in appearance.

Figure 2 is a perspective view thereof, showing the case in open position and taken on a reduced scale.

I claim:

The ornamental design for an eye glass case, as shown and described.
